UNITED STATES PATENT OFFICE

114,979

DESIGN FOR AN ORNAMENTATION TRANSFER SHEET FOR CHINAWARE OR THE LIKE

John H. Perry, Harrow, England, assignor to Colclough China Ltd., a limited company

Application January 23, 1939, Serial No. 82,542

Term of patent 3½ years

To all whom it may concern:

Be it known that John H. Perry, a subject of the British Empire, and resident of the town of Harrow, in the county of Middlesex, England, has invented a new, original, and ornamental Design for an Ornamentation Transfer Sheet for Chinaware or the like, of which the following is a specification, reference being had to the accompanying drawing, forming part thereof, in which, the figure is a top plan view of an ornamentation transfer sheet for chinaware or the like embodying my new design.

I claim:

The ornamental design for an ornamentation transfer sheet for chinaware or the like, as shown.

JOHN H. PERRY.
